COMBINED STRIKING, CASTING, AND BOLSTER CENTER FILLER FOR RAILWAY CAR CONSTRUCTION

Karl F. Nystrom, Nashotah, Wis., assignor to International Steel Company, Evansville, Ind., a corporation of Indiana

Application December 1, 1950, Serial No. 198,633

12 Claims. (Cl. 105—420)

1

My invention relates broadly to railway rolling stock construction and more particularly to a construction of a combined striking casting and bolster center filler for railway car construction.

One of the objects of my invention is to provide a construction of composite striking casting and bolster center filler for railway car construction.

Another object of my invention is to provide a construction of composite striking casting and bolster center filler in which the casting is chamfered at its longitudinally extending edges to be readily aligned and installed within the interior of the center sill.

Another object of my invention is to provide a construction of composite striking casting and bolster center filler wherein the casting is provided with a recessed top to facilitate the welding of the casting in the end of the center sill of the car underframe and to permit the laying of a car floor in a uniform plane over both the striking casting and bolster center filler.

Still another object of my invention is to provide a composite striking casting and bolster center filler carrying projecting webs thereon for facilitating the connection of the composite casting to the car underframe.

Still another object of my invention is to provide a construction of composite striking casting and bolster center filler which may be readily welded with the sill of a car underframe with the parts so proportioned as to minimize weight or mass while providing large welding contact with the center sill.

A further object of my invention is to provide a construction of combination striking casting and bolster center filler having laterally extending bolster lugs thereon for facilitating installation in a car underframe and welded connection to the bolster lugs that are placed in shear as distinguished from conventional butt weld construction.

Other and further objects of my invention reside in an improved construction of composite striking casting and bolster center filler as set forth more fully in the specification hereinafter following by reference to the accompanying drawings in which:

Figure 1 is a top plan view of the composite striking casting and bolster center filler, the casting being broken away along one-half of the longitudinal axis thereof and illustrated in section with parts of the weld connection in shear between the composite casting with the car underframe shown in section; Fig. 2 is a longitudinal sectional view taken on line 2—2 of Fig. 1; Fig. 3

5 is a vertical transverse sectional view taken on line 3—3 of Fig. 2 and illustrating the connection of the composite casting of my invention with the center sill; Fig. 4 is a vertical transverse sectional view taken on line 4—4 of Fig. 2; Fig. 5 is a vertical transverse sectional view taken on line 5—5 of Fig. 2; Fig. 6 is a vertical transverse sectional view taken on line 6—6 of Fig. 2; Fig. 7 is a fragmentary view of the bolster plate construction partially broken away and shown in section and illustrating the coaction of the center filler portion of the composite casting therewith; and Fig. 8 is a transverse sectional view taken on line 8—8 of Fig. 6.

10 My invention is directed to a construction of composite casting forming both a striking casting with integral front draft lugs and a bolster center filler. The parts of the casting are so proportioned that the casting may be readily welded into the end of the center sill of a railway car underframe where the top of the composite casting is recessed to enable the casting to be aligned with the top of the center sill and with the top bolster plate for supporting a car floor in a uniform plane over both the top of the striking casting and the top of the bolster center filler. I provide means for connecting the composite casting in shear with the car underframe. The end of the composite casting has the longitudinally extending corners thereof chamfered to facilitate entry of the composite casting into the end of the center sill and permit a welding connection to be readily made between the composite casting and the center sill. A relatively short connecting end is provided on the composite casting for establishing a welded connection with the center sill, the short connecting end minimizing weight of the casting and being formed into four prongs which establish large welding surface contact with the undersides of the center sill. The composite casting minimizes assembly time and predetermines the uniform spacial relation between the striking casting and the bolster center filler.

15 Referring to the drawings in more detail reference characters 1 and 2 indicate the coacting sections of the longitudinally extending center sill of a railway car underframe having top coplanar coacting extensions 1a and 2a, vertical web portions 1b and 2b and bottom horizontally extending flange portions 1c and 2c. The center sill, in the construction of my invention, terminates in a position just short of the bolster center filler as represented more clearly in Figs. 1 and 2. Into the end of the center sill I insert the composite casting of my invention. The

casting is shown generally at 3 including the striking casting 4 at one end thereof and the integrally connected bolster center filler 5 adjacent the other end thereof. The composite casting 3 comprises an inverted member having a flat top 6, a pair of spaced side walls 7 and 8 and a pair of outwardly directed horizontally extending coplanar flanges 9 and 10. The bolster center filler end of the casting has an integrally connected circular portion 11 co-extensive with an upwardly extending journaling means 12 connected through reinforcing webs 14 and 15 with the vertically extending webs 7 and 8 of the casting and through webs 16 and 17 with the bottom of the casting. Thus the journaling means 12 is reinforced both laterally and longitudinally within the composite casting. Transverse reinforcement of the composite casting is accomplished through laterally extending webs 18 and 19 and transverse web 20. The exterior surfaces of the webs 7 and 8 are provided with outwardly directed webs 21, 22, 23 and 24 having external surfaces which are inclined in a direction toward the opposite sides of the railway car structure which provide connecting means for the welding of bolster plates 25, 26, 27 and 28 thereto extending in directions inclined toward each other to the sides of the car underframe. The upper bolster plate 29 and the lower bolster plates 30 and 31 extend transversely across the underframe of the car and connect to the sides of the underframe in positions adjacent the connection of plates 25, 26, 27 and 28 with the sides of the underframe. The lower bolster plates 30 and 31 abut with the edge of the horizontally extending flanges 9 and 10 of the composite casting. Strips 30a and 31a are welded in a lapped joint across the flanges 9 and 10 and the ends of bolster plates 30 and 31 as shown.

The end of the composite casting terminates in four prongs shown more clearly in Fig. 3 at 32, 33, 34 and 35. These prongs form substantially right angular sections and are tapered to the end of the casting. The peripheral corners of the prongs are chamfered as represented at 32a, 33a, 34a and 35a. The chamfered corners 32a and 33a facilitate the entry of the composite casting beneath the center sill while the chamfered corners 34a and 35a facilitate the welding of the composite casting beneath the end of the center sill. Each of the prongs form means for welding the composite casting into the end of the coacting sections 1-2 of the center sill. The welded connections are shown at 32b, 32c, 33b, 33c, 34b and 35b. The composite casting thus welded, forms an extension of the center sill, enabling the center sill to be furnished in a much shorter length than the conventional center sill.

The plates 25, 26, 27 and 28 shown more clearly in Fig. 7 extend from the bolster center filler portion of the composite casting to the opposite sides of the railway car structure shown at 36 and 37. The sides 36 and 37 of the car structure are provided with short vertically extending lugs 38-38' and 39-39' to the sides of which the ends of plates 25, 26, 27 and 28 are welded or otherwise secured. Thus the composite casting is connected with the bolster plates 25, 26, 27 and 28 with the welds subject to shear stresses with greater strength than joints of the conventional butt weld type.

The transversely extending upper bolster plate 29 and the lower bolster plates 30 and 31 extend across the underframe of the car and

connect to the sides of the underframe in positions adjacent the connection of plates 25, 26, 27 and 28 with the sides of the underframe. The laterally extending lower bolster plates 30 and 31 terminate coplanar with flanges 9 and 10 spaced from opposite sides of the depending circular portion 11 of the composite casting.

The striking portion of the composite casting is integrally connected with the sides 7 and 8 of the composite casting as shown more particularly in Figs. 1, 2 and 5 consisting of the front draft lugs 49 and 44 and the rearwardly extending slotted bearing surfaces 42 and 43 for connection with the draft key indicated in dotted line position at 44. The bearing surfaces 42 and 43 are spaced uniformly from each other and are tapered from a minimum width immediately behind the front draft lugs to a maximum width remote from the front draft lugs and projecting on opposite sides of the side walls 7 and 8 of the composite casting.

The rearward portion of the composite casting has the top 45 thereof laterally recessed as represented at 46 for the lateral passage of the top plate 29 of the bolster center filler assembly and to allow coplanar alignment of the top portions 1 and 2 of the center sill with the top plate 29 and with the top 45 of the composite casting. This recessed arrangement insures the support of the flooring 47 of the car in a uniform plane so that the junction of the center sill with the composite casting presents no displacement in level throughout the car underframe.

Thus I provide a composite casting which is readily assembled by a short end connection into the end of the center sill which saves the weight and material of the normally co-extensive end portions of the center sill in the car underframe construction. The composite castings weld to opposite ends of the center sill at opposite ends of the car underframe and thus considerably shorten the length of the center sill normally required in car underframe construction. The connection of the composite casting with the bolster plates is established with the welds subject to shear stresses thus greatly strengthening the assembly of the composite striking casting and bolster center filler as compared to butt weld construction. The recessed top of the composite casting in coaction with the top bolster plate and the top of the center sill greatly facilitates the assembly operation for the subsequent laying of the car floor on a uniform level.

While I have described my invention in certain of its preferred embodiments, I realize that modifications may be made and I desire that it be understood that no limitations upon my invention are intended other than may be imposed by the scope of the appended claims.

What I claim as new and desire to secure by Letters Patent of the United States is as follows:

1. A combined striking casting and bolster center filler for railway cars comprising in combination with the center sill of a railway car formed by an inverted channel-shaped structure terminating in a pair of oppositely extending horizontally disposed coplanar flanges, a casting terminating in tapered prongs aligned to enter the end of the inverted channel-shaped structure and having composite curved and linear edge portions extending adjacent the interior walls of said inverted channel-shaped structure for effecting a welded connection there-

with, said casting including an integrally formed bolster center filler adjacent said tapered prongs and a striking casting integrally connected therewith at the opposite end of the casting, said casting terminating in oppositely extending horizontally disposed coplanar flanges substantially aligned with the aforesaid flanges on said center sill.

2. A combined striking casting and bolster center filler for railway car construction comprising in combination with the center sill of a railway car where the center sill is formed by an inverted channel-shaped structure terminating in horizontally disposed coplanar oppositely extending flanges, a casting having spaced members in each corner of one end thereof shaped to enter the end of the channel-shaped structure forming said center sill, said members having peripheral edge portions disposed adjacent the interior walls of said inverted channel-shaped structure for effecting a welding connection therewith, a striking casting integrally connected with the opposite end of the aforesaid casting and an integrally formed bolster center filler disposed between said striking casting and the connection of said first mentioned casting with said center sill, said casting including a pair of oppositely directed horizontally extending coplanar flanges extending in alignment with the flanges on said center sill.

3. A combined striking casting and bolster center filler for railway car construction as set forth in claim 2 in which spaced members on the end of said casting which enters the channel-shaped structure of the center filler are constituted by four tapered tongues of right angular section, said tongues being tapered from a position adjacent the end of said casting to the extremity of said casting and providing working space therebetween for welding the peripheral edge portions thereof to the interior walls of the center sill.

4. A combined striking casting and bolster center filler for railway car construction as set forth in claim 2 in which the top of said casting adjacent said bolster center filler is recessed below the plane of the co-extensive portion of the top of the casting for receiving and supporting a transversely disposed bolster plate having the top surface thereof coplanar with the top of the channel-shaped structure of the center sill.

5. A combined striking casting and bolster center filler for railway car construction as set forth in claim 2 in which the spaced members forming the connecting means between the end of the casting and the channel-shaped structure of the center sill are constituted by four tapered tongues of right angular cross-section and where the peripheral edges of the right angularly tapered tongues at the exterior corners thereof are each chamfered at the positions where the casting enters the channel-shaped structure for facilitating insertion of the casting in the end of the center filler and the entry of a welding tool therebetween for welding the casting to the center sill.

6. A combined striking casting and bolster center filler for railway car construction as set forth in claim 2 in which the opposite exterior sides of said casting are provided with vertically extending lugs having external surfaces extending in transverse directions inclined toward each other forming connecting means for bolster

plates extending therefrom to the underframe construction of a car.

7. A combined striking casting and bolster center filler for railway car construction as set forth in claim 2 in which said bolster center filler includes a downwardly depending circular portion concentrically disposed with a bolster pin connection means and in which the top of said casting above said downwardly extending circular portion is recessed to receive and support a transversely extending upper bolster plate with the top surface thereof coplanar with the top surface of the center sill, and a pair of transversely extending lower bolster plates extending substantially coplanar with the flanges on said channel shaped structure, the depending circular portion of said bolster center filler extending between the ends of the said lower transversely extending downwardly bolster plates.

8. A combined striking casting and bolster center filler for railway car construction comprising a casting having a bolster center filler adjacent one end thereof and a striking casting on the opposite end thereof, in combination with a car underframe including side walls and a center sill, bolster plates extending between the opposite side walls of the car underframe and the sides of said casting, a coacting upper bolster plate and a pair of lower bolster plates extending between the sides of the car underframe and the top and bottom of said casting, the bolster center filler of said casting including a depending circular recessed portion extending in a position between the ends of the lower bolster plates and said casting being recessed at the top thereof for receiving and supporting said upper bolster plate with the top surface of said upper bolster plate disposed in alignment with the plane of the top of said center sill.

9. A car underframe construction comprising in combination with side wall members and a longitudinally extending center sill formed by an inverted channel-shaped structure having coplanar horizontally extending flanges, a casting comprising an inverted channel-shaped structure formed by a top portion, a pair of vertical side walls and a pair of oppositely directed horizontally extending flanges, a striking casting on the end of said casting and a bolster center filler adjacent the opposite end thereof, the top of said casting immediately above said bolster center filler having a recessed portion contiguous with the side walls thereof and projecting into the end of the channel-shaped structure of the center filler, a welded connection between the end of said casting and said center filler, connection means carried by the exterior of the sides of said casting and having angularly disposed surface portions thereon, connecting plates extending between the aforesaid angularly disposed surface portions and the side walls of said car underframe, said bolster center filler including a depending circular portion concentrically surrounding a bolster pin supporting portion, an upper bolster plate extending transversely between the side walls of said car underframe transversely through the recessed portion of the top of said casting and supported thereby, said upper bolster plate having the plane of the top surface thereof disposed in alignment with the plane of the top of the center sill and a pair of lower bolster plates extending transversely of the car underframe and connected at opposite ends with the sides thereof, said lower bolster plates terminating in substantially coplanar alignment with said horizontally extend-

ing flanges and a pair of strips overlapping said flanges and the ends of the lower bolster plates and forming a welded connection therewith.

10. A car underframe construction as set forth in claim 9 in which the connection means carried by the sides of said casting are constituted by vertically extending lugs and in which the car underframe is also provided with vertically extending lugs substantially aligned with the lugs on said casting and vertically disposed plates interconnecting said lugs in positions for resisting shear stresses.

11. A car underframe construction as set forth in claim 9 in which the connection means carried by the exterior sides of said casting are constituted by four linear outwardly tapered tongues positioned beyond the terminating end of said center sill.

12. A car underframe construction as set forth in claim 9 in which the top surface of the upper bolster plate, the top surface of said center sill and the top surface of said casting contiguous with said striking casting are all coplanar and serve as a horizontal support for a car floor in a continuous horizontal plane.

KARL F. NYSTROM.
